LAMP FINISHING MACHINE

Victor Anderson, Cliffside Park, N. J., assignor to
 Alfred Hofmann & Company, West New York,
 N. J., a corporation of New Jersey

Application March 6, 1935, Serial No. 9,683

13 Claims. (Cl. 140—119)

This invention relates to lamp finishing machines, which deal with the attaching of the base or end member to the glass container or bulb of an incandescent electric lamp, and the subsequent operations thereon; the present invention being directed particularly to an improvement in the mechanism for properly disposing each of the loose leadwires, that is, bending or curling it into its intended position, and preferably severing the excess length of the leadwire, preparatory to the soldering of such bent and severed end to a metallic portion of the base.

As an example of a lamp finishing machine of the kind referred to reference is made to co-pending application of C. B. Palucki, Serial No. 722,627, filed April 27, 1934. The present invention is illustratively shown applied to the machine disclosed in said prior application, and many features and details are omitted herefrom for brevity, as reference may be made to the prior application therefor.

The general object of the present invention is to improve the leadwire bending and severing operations as to efficiency and accuracy of operation and uniformity of product. A particular object is to provide a bending and severing mechanism which will operate uniformly and accurately upon incandescent lamps notwithstanding certain irregularities in dimension and form of lamps. In other words the mechanism hereof is self-adapting to such irregularities, thus avoiding well understood difficulties in the art due to inevitable variations occurring in the usual lamps as supplied to the finishing machine.

The standard lamp base has a recess adjacent to each issuing leadwire, such as a groove for the side wire and a central hole through which the end wire extends, into which recess the wire is to be snugly disposed; and it has been found that if this recess is slightly offset it may interfere with the bending operation and impair the operation and product. These variations may be due to errors in the relative positions of the assembled parts of each lamp, or to errors in the form of any one or more parts, thus altering to a substantial extent the relation of the leadwires to the bending and severing mechanism, such error also frequently arising by reason of variations in the chucking of the lamps in the heads of the machine, throwing relatively out of alinement the bending and severing mechanism and the portion of the lamp to be operated upon thereby. The difficulty referred to is more pronounced with the end

leadwire and the invention is shown applied to afford a correction thereof.

Other and further objects and advantages will be explained in the following description of an illustrative embodiment of the invention or will be understood by those conversant with the subject. To the attainment of such advantages, the present invention consists in the novel leadwire bending and severing mechanism and the novel features of combination, arrangement and construction herein illustrated or described.

In the accompanying drawings Figure 1 is an axial vertical section view of a mechanism embodying the invention, with the operating instrument raised or retracted.

Fig. 2 is a section view similar to Fig. 1, but only partly in section, and showing the parts in a different position, with the operating instrument advanced or lowered into active relation to the lamp.

Fig. 3 is a horizontal section taken on the line 3—3 of Fig. 2.

Fig. 4 is an elevation view looking toward the right sides of Fig. 1 or 2, with the parts in the same retracted position as in Fig. 1; this view corresponding in part with Fig. 7 of said prior application. Fig. 4^a is a view similar to Fig. 4 of certain parts omitted from the upper part of Fig. 4, the two figures overlapping and constituting in effect a single figure.

Figs. 5, 6 and 7, on an enlarged scale, are axial sectional views or diagrams showing successive positions of certain parts before, during and after the operation.

So far as reference characters herein are found in said prior application they refer to corresponding parts, but new or different parts herein bear references not in the prior application.

A conventional lamp is indicated comprising the bulb A, at the upper part of which is assembled and united a so-called base, comprising the screw threaded metallic sleeve C and the metallic button or disk D at the end, the disk being separated from the sleeve by insulating material B'. Connected with the lamp filament are the two leadwires, the end leadwire E issuing through the usual central recess or perforation D' in the disk D, while the side leadwire F issues between the bulb and the lower edge of the sleeve C, adjacent to the slight circumferential recess or groove F' into which it is to be bent. The present invention relates to the bending or curling of any leadwire into its recess, but especially to the curling of the end leadwire E into recess

D', the operating instrument being adapted to enter the recess or central hole and there to take part in curling and preferably severing the wire leaving an exposed portion E' as seen in Fig. 7 snugly adjacent the recess and ready to receive a portion of solder.

The assembled lamps are loaded into the successive heads of the machine, wherein the attachment between the bulb and base is first effected, and thereafter the bending and severing of the leadwires, followed by the soldering thereof to the base. Many parts of the machine except those pertaining to the bending and severing of the leadwires are omitted herefrom. As in the prior application there is shown a rearwardly extending fixed bracket 124 formed with a vertical way 125 for the bending and severing instrument 130 to be described. The bracket 124 carries also a horizontal way 126 for an operating rack 155 to be described. Extending above bracket 124 is a vertical extension 127 from which project upper and lower bearings 128 and 129 constituting vertical guides for parts 133^a and 134 to be described.

The bending and severing instrument 130 is shown as comprising a first or mandrel member 131 and cooperating with or surrounding it a second or relatively rotary member 139, generally similar to corresponding parts in said prior application. The mandrel 131 is preferably non-rotary and takes part in the bending and preferably in the severing; while the member or bender 139 is rotary and cooperates in the bending and preferably in the severing as well; although the mandrel might be rotated with similar effect. In its bending function the member 139 engages the loose wire and curls it around the mandrel close to the base. In its severing function it cooperates with the mandrel to shear off the excess wire.

As best shown in Figs. 5-7 the mandrel member is preferably formed with a rounded cylindrical extension or nose 131^a sufficiently small to enter the disk recess D'. The wire is to be wrapped about its thicker body above. The mandrel is shaped also to afford a shearing edge 132 cooperating with the member 139 as will be described. Along the lower part of the member 131, including its extension 131^a, is formed a notch or longitudinal groove 132^a sufficiently large to accommodate or position the leadwire E, when the nose 131^a occupies the disk recess, as well shown in Fig. 6. Thus the issuing part of the wire is held at one side while its extension is bent around the mandrel.

Fig. 5 illustrates the nature of the irregularities which are frequently found in commercial lamps to be finished. Thus, owing to errors in form or contour, or relative location of the elements of the lamp, the mandrel member 131 of the bending and severing instrument, descending in its normal line of operation shown, is likely to find the recess D' offset as shown, which would tend to obstruct the accuracy of the operation, or even to impair the quality of the operation and product, or damage the latter beyond repair; and frequent recurrences would tend to the injury of the instrument or mechanism.

To the overcoming of these drawbacks the present invention involves a novel arrangement wherein the operating instrument, or at least the active end thereof, is mounted in a yielding or floating manner, preferably resilient, so that it can adjust itself to the existing irregularity, and thereafter return to normal position. For ex-

ample if the mandrel member descends in the position shown in Fig. 5 it is readily able, with this invention, to shift laterally so as to descend correctly into the disk recess, as seen in Fig. 6, without interfering with the operative movements of the instrument.

Referring to the sectional views Figs. 1, 2 and 3, the mandrel member 131 is shown as having a long shank or stem 133 which extends upwardly in a normally axial position, and at its upper end is clamped and anchored within a shiftable slide block 134, above which is a slidable extension 133^a. These mountings permit the necessary vertical movement of the mandrel member between the position shown in Figs. 1 and 4, to which, between operations, the mandrel is lifted or retracted and its lowered or advanced position of Figs. 2, 5 and 6, the block 134 sliding in the bearing 129 and the extension 133^a in the bearing 128.

To afford relative rotary movements between members 131 and 139, the mandrel member and its shank 133 are preferably prevented from rotation, for example, by reason of a groove 134^a in the block 134, engaged by a key 129^a mounted in the bearing 129, permitting vertical while preventing rotary movements. A spring 136 is inserted between the block 134 and the upper bearing, thus tending always to force downwardly the shank 133 and the mandrel member 131.

By the described arrangement the mandrel 131 is self-adaptable to variations in lamp base recess position, since the upper end of its shank 133 is anchored in block 134 but the shank itself is a rod which can deflect or bend in any transverse direction, the active end of the mandrel thus being resiliently yieldable or of floating character for the stated purposes.

The longitudinally shiftable and rotary member 139 preferably carries both a bending means or hook 140 for bending the wire about the mandrel and a severing edge or cutter 141 for shearing off the excess wire; although manifestly these functions could be separated and other means used for severing the wire. The member 139 is fitted to advance with the mandrel until the latter engages and is stopped by the lamp base, and then to advance further, this relative advance bringing the bender 140 and cutter 141 to operative position, following which the member 139 is rotated to perform both operations closely against the lamp base.

The fittings and actuation may be as follows. The member 139 is extended as a screw head 142 threaded into a carrying sleeve or operating shank 145, with a lock nut 142^a holding the parts. A collar 143 is clamped on the head 142 by a set screw 144, and this collar carries the wire-engaging hook or bender 140, which is shaped to gather in the wire and wrap it around the mandrel.

The member 139 and its head 142 preferably fit snugly upon the mandrel shank 133, being both shiftable and rotatable thereon. To cooperate in the self-adapting or floating action of the mandrel the member 139 is rendered transversely shiftable therewith by reason of its sleeve shank 145 being mounted loosely in an outer rotatable sleeve 145^a. The inner and outer sleeves are compelled to rotate together by reason of a slot or way 145^b in the inner sleeve engaged by a fin or key 145^c in the outer sleeve. The bore of the outer sleeve being substantially larger than the inner or bender sleeve the latter has transverse play, as illustrated in Figs. 2 and 3, accommodat-

ing itself to any transverse displacement of the mandrel as illustrated by Figs. 5 and 6.

- The outer sleeve 145 constitutes an elongated ring or hollow rotor, preferably mounted against 5 longitudinal sliding but rotatable in the vertical way or bearing 125. For rotating it and thereby the inner sleeve and bender member 139 the outer sleeve is formed with outer teeth 146, engaged by a rack 155 to be described.
- 10 For sliding longitudinally the inner sleeve 145 and thereby the bending and severing member 139 the former at its upper end has a circumferential groove 147 engaged by roller studs 148 on a fork 149 at the end of a rockarm 150, see Fig. 15
- 15 4. The arm 150 is part of a lever pivoted at 151 on the bracket 124, its other arm 152 being connected by rod 173 with operating mechanism shown in the prior application. A spring 153 pulls down arm 150, tending to lower or advance 20 the sleeve 145.

The advance and retraction of the bending and severing member 139 are thus effected by timed connections, and this operation actuates also the mandrel member 131, since the block 134 of 25 the latter is pressed by spring 136 into contact with sleeve 145, the members thus lowering together until the mandrel meets the lamp, after which the other member lowers relatively into bending and severing relation to the mandrel.

30 In this way the actual bending and severing are performed very close to the lamp base as is desirable to facilitate the subsequent soldering.

The rotation of the bending and severing member 139 relatively to the mandrel member 131 is effected by a rack bar 155, the teeth of 35 which engage the teeth 146 of the outer sleeve 145^a. The rack 155 slides horizontally in the way 126 and it has an outwardly projecting stud 156 extending through a slot in a cover plate 157. 40 By this arrangement the reciprocation of the rack 155 rotates the outer sleeve 145^a which in turn rotates the inner sleeve 145 carrying the bending and severing member 139. The timed connections for effecting the rotation of these 45 parts following their advance to the work may be as in said prior application. A connecting rod 160 is herein shown extending to the stud 156 of the rack from a lever arm 161, which may be swung by cam actuation in coordination with the 50 actuation of the connecting rod 173 by which the longitudinal movements are effected.

As the initial function of member 139 is the bending of the wire about the mandrel 131 the invention may be considered, without reference 55 to the particular mode of severance, as the combination with means for holding an electric lamp of the kind composed of a bulb and a recessed base, and having one or more leadwires extending from the base, of mechanism for bending 60 such a leadwire into position to be attached or soldered to the recessed portion of the base, comprising a bending instrument consisting of a mandrel member and cooperating bender member, said members being advanceable longitudinally 65 nally to the lamp base, and the mandrel member being adapted to enter and engage the base recess during bending, and the bender member being relatively movable to bend the wire about the mandrel, means mounting said instrument to 70 receive longitudinal advancing and retracting movements and to yield transversely, preferably resiliently, as may be requisite for the entry of the mandrel member into the base recess in varying positions of the latter, and timed connections for causing the advancing and retract-

ing movements and the cooperative bending movement of said members. The mandrel is relatively non-rotatable and has the notch or shoulder 132^a positioning the issuing wire, while the bender rotates and so carries the wire about 5 the mandrel close to the base.

The mandrel shank is a long rod and therefore bendable in all transverse directions for the flexible yield or play of the mandrel. The bender has a sleeve shank surrounding the mandrel shank, 10 and exterior means for rotating it while permitting the transverse play and longitudinal movements. Such rotating means comprises the outer sleeve 145^a which surrounds the other with clearance, with gearing to turn the outer sleeve and a 15 spline or similar connection between the sleeves.

The described objects are thus obtained. Within ample limits for practical purposes, the members 131 and 139, having operative movements as described, have also the transverse yield 20 for the adaptation of the members to variations in the position, so that the mandrel end can enter the base disk hole and ensure proper operations of bending and severing. Broadly the objects are obtainable by any arrangement 25 having provision for relative transverse yield as between the leadwire bending and severing mechanism and the lamp holding means to ensure proper relation of the mechanism to lamps of 30 varying structure.

It has thus been described, in a lamp finishing machine, a mechanism for disposing properly the loose leadwires by bending and severing the same, embodying the principles and attaining the objects of the present invention. Since however many matters of combination, arrangement and construction may be variously modified without departing from the principles of the invention it is not intended to limit the invention to such matters except to the extent set forth in the 35 appended claims.

I claim:

1. In combination with a head having means for holding an electric lamp of the kind composed of a bulb and a recessed base, and having 45 one or more leadwires extending from the base, mechanism for bending such a leadwire into position to be attached or soldered to the recessed portion of the base and for severing its excess length, comprising a mandrel member advanceable longitudinally to the lamp base and adapted to enter and engage the base recess during bending and severing, a bending and severing member cooperable with the mandrel member, means mounting said members to receive longitudinal 55 advancing and retracting movements and to yield transversely as necessary for the entry of the advancing mandrel member into varying positions of the base recess, and connections for causing the advancing and retracting movements and 60 the cooperative bending and severing movements of said members.

2. In combination with a head having means for holding an electric lamp of the kind composed of a bulb and a recessed base, and having 65 one or more leadwires extending from the base, mechanism for bending such a leadwire into position to be attached or soldered to the recessed portion of the base and for severing its excess length, comprising a mandrel member held 70 against rotation but advanceable longitudinally to the lamp base and adapted to enter and engage the base recess during bending and severing, and having a notch or shoulder engaging and positioning the leadwire, a bending and severing 75

- member cooperable with the mandrel member, and having a hollow shank surrounding the mandrel member, and advanceable relatively to the mandrel member, and rotatable for the bending and severing operations, means mounting said members to receive longitudinal advancing and retracting movements and to yield resiliently transversely as necessary for the entry of the advancing mandrel member into varying positions of the base recess, and connections for causing timed advancing and retracting movements of said members and the cooperative rotary movements of the bending and severing member.
3. In combination with means for holding an electric lamp of the kind composed of a bulb and a recessed base, and having one or more leadwires extending from the base, mechanism for bending such a leadwire into position to be attached or soldered to the recessed portion of the base, comprising a bending instrument consisting of a mandrel member and cooperating bender member, said instrument being advanceable longitudinally to the lamp base and the mandrel member being adapted to enter and engage the base recess during bending, means mounting said instrument to receive longitudinal advancing and retracting movements and to yield transversely as may be requisite for the entry of the mandrel member into the base recess in varying positions of the latter, and timed connections for causing the advancing and retracting movements and the cooperative bending movement of said members.
4. In combination with means for holding an electric lamp of the kind composed of a bulb and a recessed base, and having one or more leadwires extending from the base, an instrument for bending such a leadwire into position to be attached or soldered to the recessed portion of the base, comprising a mandrel member and cooperating bender member, said instrument being advanceable longitudinally to the lamp base, and the mandrel member being adapted to enter and engage the base recess during bending, and the bender member being relatively movable to bend the leadwire about the mandrel member, means mounting said instrument to receive longitudinally advancing and retracting movements and to yield resiliently transversely for the entry of the mandrel member into the base recess in varying positions of the latter, and connections for actuating said members.
5. The combination as in claim 4 and wherein the mandrel has a long rod-like shank anchored at its rear end and bendable in all transverse directions for the yielding of the mandrel.
6. In combination with means for holding an electric lamp of the kind composed of a bulb and a recessed base, and having one or more leadwires extending from the base, mechanism for bending such a leadwire into position to be attached or soldered to the recessed portion of the base, comprising a mandrel member and cooperating bender member, said members being advanceable longitudinally to the lamp base, and the mandrel member being adapted to enter and engage the base recess during bending, and the bender member being relatively rotatable to bend the leadwire about the mandrel member, and means mounting said mandrel to receive longitudinally advancing and retracting movements and to yield resiliently transversely to afford play for its entry into the base recess in varying positions of the latter.
75. 7. The combination as in claim 6 and wherein

the bender member has a sleeve portion surrounding the mandrel, and exterior means for rotating it while permitting longitudinal movements and transverse play.

8. In combination with means for holding an electric lamp of the kind composed of a bulb and a recessed base, and having one or more leadwires extending from the base, means for bending such a leadwire into position to be attached or soldered to the recessed portion of the base, comprising a mandrel member and cooperating bender member, said members being advanceable longitudinally to the lamp base, and the mandrel member being adapted to enter and engage the base recess during bending, and the bender member being relatively rotatable to bend the leadwire about the mandrel member, said mandrel having a long flexible shank and a longitudinally slidible block in which the shank rear end is anchored, said bender having a sleeve shank surrounding the mandrel shank, and rotatable thereon, an outer sleeve or ring surrounding the bender shank with clearance affording transverse play of the mandrel and bender shanks, and means for rotating the bender shank.

9. In combination with means for holding an electric lamp of the kind composed of a bulb and a recessed base, and having one or more leadwires extending from the base, means for bending such a leadwire into position to be attached or soldered to the recessed portion of the base, comprising a mandrel member and cooperating bender member, said members being advanceable longitudinally to the lamp base, and the mandrel member being adapted to enter and engage the base recess during bending, and the bender member being relatively rotatable to bend the leadwire about the mandrel member, said mandrel having a long flexible shank and a longitudinally slidible block in which the shank rear end is anchored, said bender having a sleeve shank surrounding the mandrel shank and rotatable thereon, an outer sleeve or ring surrounding the bender shank with clearance affording transverse play of the mandrel and bender shanks, and means for rotating the bender shank, comprising a spline connection between the bender and outer sleeves permitting longitudinal movement of the former and gearing to rotate the outer sleeve.

10. In combination, the longitudinally movable mandrel with its bendable shank, the bender with its sleeve shank surrounding the mandrel shank, the outer rotatable sleeve surrounding the bender sleeve with a clearance to permit transverse bending of the mandrel shank and displacement of the bender sleeve, and a connection between the outer and bender sleeves whereby the former may rotate the latter while allowing its longitudinal and transverse movements.

11. In a lamp finishing machine a lamp holding means for holding the lamp with a leadwire projecting from the lamp base, a leadwire bending and severing mechanism adjacent to such holding means with bending and severing means shiftable to and from the lamp, and said mechanism having a provision for relative yield of the bending and severing means transversely to the shifting thereof to ensure proper relation of said mechanism to lamps held in said means, notwithstanding variations in such lamps.

12. In a lamp finishing machine a holding means for a lamp, a leadwire bending instrument shiftable to and from the lamp and rotatable for bending the wire, and means for operating said instrument, comprising a provision for relative

yield of the instrument relative to its axis of rotation, thereby to afford self centering of said instrument to a lamp held in said holding means.

13. In combination, a longitudinally movable mandrel having a laterally displaceable shank, a bender with its sleeve shank surrounding the mandrel shank, an outer rotatable sleeve sur-

rounding the bender sleeve with a clearance to permit lateral displacement of the mandrel shank and bender sleeve, and a connection between the outer and bender sleeves whereby the former may rotate the latter while allowing its longitudinal and lateral movements.

VICTOR ANDERSON.
